STREAMLINED LOCOMOTIVE

Chase H. Knowlton, Greenburgh, N. Y., and George M. Davies, Fair Lawn, N. J., assignors to The New York Central Railroad Company, a corporation of New York

Application November 3, 1938, Serial No. 238,674

6 Claims. (Cl. 105—2)

The advent of streamlining locomotives confronted builders with many problems relative to necessary parts of the locomotive which prevent ed the streamlining.

5 Our invention relates to the streamlining of the front end of the locomotive, taking care of the front end of the boiler, and the pilot and intermediate parts; and our invention consists of the parts and combination of parts hereinafter 10 pointed out.

In the drawings:

Figure 1 is a perspective view of the front end of a locomotive showing our improvement in streamlining.

15 Figure 2 is a similar view of the front end of a locomotive showing the two halves constituting the streamlining proper open in order to disclose their construction.

20 Figure 3 is a side elevation on an enlarged scale of one of the halves comprising the streamline proper, viewing it from the inside.

Figure 4 is a front elevation of the co-acting half of the streamlining hood, viewing it from the outside.

25 Figure 5 is a fragmentary side elevation of a portion of one of the hoods showing more particularly the arrangements of the slits for permitting the egress of heated air that may accumulate within the hood.

30 Figure 6 is a detailed sectional view taken on line 6—6 of Figure 3.

Figure 7 is a horizontal section taken on line 7—7 of Figure 4, looking in the direction of the arrows.

35 Figure 8 is a transverse vertical section taken on the line 8—8 of Figure 3, and showing the construction of the flange and the portion of the hood.

Figure 9 is a horizontal section taken on line 40 9—9 of Figure 1, and showing more particularly the construction in arrangement of the hand holds for permitting work upon the searchlight.

Figure 10 is a detail vertical section on line 45 10—10 of Fig. 1 through the cowling showing in full and dotted lines the sliding foot rest.

The reference numeral 1 designates the locomotive in which the front wall of the smoke box is designated by the numeral 2 which is provided with a door 3 suitably hinged.

50 To streamline the front end of the boiler we provide two streamlined doors 4 and 5 complementing each other and forming a hemispherical cowling for the front end of the boiler. While we have shown these doors, when closed, forming a hemisphere, it will be understood that the

shape of the doors may be such as to blend with the streamlining feature of the locomotive.

The hemispherical portion 5 is made up of a front frame 6 having strengthening ribs 7, the frame 6 being provided at its base with an integral flange like projection 8. A streamlining sheet 10 is suitably secured to this frame and to the flange 8, and the sheet 10 is hinged to the front wall of the smoke box as at 10'. It will be seen from the drawings that the front frame 6 projects substantially outwardly from the surface of the streamlining sheet 10, and constitutes a fin-like projection, or flange 11, extending from the top to the bottom edge of the frame both above and below the headlight. This fin, 15 or flange, 11 is interrupted about midway and at this point a headlight frame 12 is cast integral with the frame of the door 5. The headlight 13 is rigidly secured in this head light frame 12 and swings with the hemispherical section 5 20 when this section is moved.

The hemispherical section 4 is substantially of the same construction as the section 5 and its sheet 10 is fastened to its frame 6 and to a base flange 9 projecting therefrom and said sheet 25 is hinged at 14 to the front wall of the smoke box. The section 4 differs from section 5 in that it has a semi-circular opening 15 which is adapted to receive the head light frame 12 when the two sections are in closed position. When the two 30 sections are in closed position the fin 11 of section 5 fits snugly against the fin 16 of the section 4 and when in this position their combined width presents a substantial, as well as ornamental fin or flange outstanding from the surface of the streamlining sheets of the two sections. 35

At points above and below the headlight 13, the fins 11 and 12 are provided with sets of openings, each set comprising a counter-sunk opening 17 extending through the fins 11, and an opening 18 extending through the fin 16 and terminating at its outer end in an enlarged recess 18'.

40 A hand grip bar 19 is provided for engagement with each set of openings. Each bar 19 is formed with an enlarged bevel projection 20 adapted to fit in the countersink of the opening 17; said bar being also provided with a screw threaded portion 21 which is adapted to interengage with the screw threads in the opening 18 of the fin 45 16, a nut 22 being provided to hold the hand grip 19 from becoming accidentally displaced. The object of these grip bars is to provide hand holds or grabs for the use of an operator to support himself while standing at the front of the 50 55

locomotive and engaged in repairing or adjusting the headlight.

The cowling 23 is provided with a sliding foot rest 24 on which the operator stands while working on the headlight. This foot recess is slideable back and forth through an opening in the cowling to an advanced or projected position for use and to a retracted position when not in use. The cowling 25 covering the pilot is provided with 10 steps 26, and a similar step 27 is formed in the cowling 23 to enable the operator to climb the front end of the locomotive when necessary or desirable. The cowling 25 is also provided with a door of any desired construction which may 15 be opened to permit the locomotive coupler to be used.

The hemispherical doors 4 and 5 may be opened independently.

The flanges of the doors are secured together 20 by bolts or other appropriate devices 28 when the doors are closed. Upon disconnection of these bolts and the removable hand grabs 19 the doors may be opened.

What I claim is:

- 25 1. In a locomotive, a cowling for the front end of the boiler comprising two doors hinged to the front of the locomotive, each door being in the shape of a quarter sphere and said doors being arranged with respect to each other to form a hemispherical front for the boiler when in closed 30 position, one of the doors having a rest, and the other door carrying a headlight carrying frame adapted to be received into the recess of the first-named door in the closed position of said doors.
- 35 2. In a locomotive, a cowling for the front end of the boiler comprising two doors having inner meeting edges and hinged at their outer edges to swing toward and from each other at the front of the locomotive, one of said doors carrying at its meeting edge a headlight carrying frame and the other of said doors having a recess at its free edge to receive said frame in the closed position of the doors.
- 40 3. In a locomotive, a cowling for the front end of the boiler comprising two doors each in the shape of a quarter sphere and complementarily forming when in closed position a hemispherical cowling at the front of the boiler, said doors having meeting edges and being hinged at their outer edges to swing toward and from each other across the front of the locomotive, one of said doors having at its meeting edge, a head light carrying frame extending in part laterally therefrom and the other of said doors having a recess 45 in its meeting edge to receive the projecting part of said frame when the doors are closed, outwardly extending flanges on the meeting edges of said doors following the contour of said front edges and adapted to abut when the doors are in closed

position, and means connecting said flanges to hold the doors in closed position.

4. In a locomotive, a cowling for the front end of the boiler, comprising two doors each in the form of a quarter sphere and complementarily forming in closed position a hemispherical cowling at the front of the boiler, said doors having meeting edges and being hinged to swing toward and from each other at the front of the locomotive, one of said doors being provided at 5 its meeting edge with a headlight carrying frame projecting in part laterally beyond said edge of said door and the other of said doors having at its meeting edge a recess to receive the projecting part of the head light frame when the doors are closed, an outwardly extending flange on the front edge of each of said doors adapted to abut when the doors are in closed position, and a hand grab associated with said flanges.

5. In a locomotive, a cowling for the front end 20 of the boiler, comprising two doors each in the shape of a quarter sphere hinged at their outer edges to the locomotive and arranged to complement each other and form a hemispherical front end for the boiler, a headlight carrying frame 25 integral with the front edge of one of said doors, a headlight mounted in said frame, the other door being provided with a recess into which the head light frame fits when the doors are closed, an outwardly extending flange on the front edge of 30 each of said doors adapted to abut when the doors are in closed position, a hand grab associated with said flanges, a cowling extending from the bottom of said doors to the pilot, and a sliding step mounted on said last named cowling and 35 adapted to be moved horizontally with respect to the boiler cowling.

6. In a locomotive, a cowling for the front end of the boiler, comprising two doors each in the form of a quarter sphere hinged at their relatively outer edges to the locomotive and arranged to complement each other and form a hemispherical front end for the boiler, a headlight carrying frame integral with the front edge of one of said doors, a headlight mounted in said 40 frame, the other door being provided with a recess into which the head light frame fits when the doors are closed, an outwardly extending flange on the front edge of each of said doors adapted to abut when the doors are in closed position, a hand grab associated with said flanges, a cowling extending from the bottom of said doors to the pilot, a sliding step mounted on said second named cowling and adapted to be moved 45 horizontally with respect to the boiler cowling, a cowling covering the pilot, and steps formed in the last-named cowling.

CHASE H. KNOWLTON.
GEORGE M. DAVIES.
